APPARATUS FOR CONVEYING A MASS OF CIGARETTES FROM ONE LEVEL TO A HIGHER LEVEL

Alan K. McCombie, London, England, assignor to The Molins Organisation Limited, a British company
Continuation of application Ser. No. 345,293, Feb. 17, 1964. This application Feb. 23, 1966, Ser. No. 537,599
6 Claims. (Cl. 198—76)

This application is a continuation of my prior filed co-pending patent application Serial No. 345,293 filed February 17, 1964.

This invention relates to the conveyance of a mass of cylindrical rodlike articles such as cigarettes, cylindrical cigars or filter rods, from one level to a higher level.

The invention is mainly intended for use with the apparatus described and shown in the specification of the copending US. Serial No. 319,846 but is not limited to such use as it can be applied in any circumstances where a mass of rodlike articles is located at one level and it is necessary to transfer the articles to a higher level by movements occurring in the mass itself, that is, without the aid of trays, carrier-platform conveyors, and suchlike devices. The mass to be raised has a width equal to the length of an article and a depth of any desired amount.

In copending U.S. application Serial No. 319,846 mentioned above a large mass of cigarettes coming from a cigarette machine is collected in a compartment and cigarettes are conveyed from said mass to the cigarette hoppers of packing machines by various conveyor belts. Normally it is necessary to raise the cigarettes to deliver them to a hopper because of the relative heights of a cigarette machine and a packing machine.

The invention about to be described has a conveying arrangement capable of lifting cylindrical rodlike articles in mass, in the form of a thick column, to a height of several feet without undue disturbance or injury to the individual articles. Normally the mass to be lifted will be supported horizontally at its lower position and the lifted articles delivered to a horizontal support at the higher position, but horizontal supporting is not essential as the supports might slope somewhat. The word "level" is to be understood in this sense.

According to the invention there is provided apparatus for moving a mass of cylindrical rodlike articles such as cigarettes, cylindrical cigars or filter rods, from one level to a higher level, comprising a conveying device consisting of a passage defined by two conveyor bands, having neighbouring runs which move upward, and spaced apart by a dimension not substantially exceeding 3 inches, means for driving the bands to cause said upward movement and means for urging a mass of the articles into contact with the bands at the lower end of said neighbouring runs, whereby the mass is gripped by the bands and carried upwards. The said dimension varies somewhat according to the nature of the articles being conveyed, but 3 inches is about the practicable maximum for cigarettes. The movement is caused by friction between articles and bands and the internal friction between articles, and both factors depend to some extent on the hardness or softness of the articles, the nature of the external surface of the articles, for example, the nature of the paper wrapper of cigarettes and, possibly, the condition (moisture content) of articles such as cigarettes. As the apparatus is primarily intended for use with apparatus according to the specification quoted above, or in similar work, where a deep mass at one level is to be raised to a higher level, the cross-section of the mass to be lifted, that is, its depth, diminishes as it moves into contact with the bands at the said lower end. This reduction in

cross-section may be obtained by spacing the neighbouring runs of the bands at a desired width and providing the band which operates on the upper part of the mass at the low level with a cylindrical weight which hangs in the lower loop of the band, and tensions it, and is positioned to define a path of converging curved shape, with an entry of a depth equal to the cross-section of the mass at the low level and a thickness at the exit equal to the cross-section of the mass to be carried up between the neighbouring runs of the bands. The weight merely hangs in the loop but it is controlled laterally and so its only effect is to tension the band, and the runs of the band retain their upwardly directed positions. Side flanges embrace the weight and provide lateral guides and for this purpose the weight is shaped as a ring and a rotatable shaft passing through said ring carries two discs to provide the said flanges.

In a modified arrangement the band which operates on the upper part of the mass at the lower level is supported by a large pulley, which rotates on a fixed axis (which may be adjusted) the pulley being positioned to define a path of the same converging curved shape as before.

The conveyor bands may be vertically disposed but it is possible to have them sloping backwards from the vertical plane so that the upward run is at an angle of less than 90° to the lower level.

The invention will be more fully described with reference to the accompanying drawings in which:

FIGURE 1 shows one arrangement according to the invention and,

FIGURE 2 shows a modified arrangement.

As shown in FIGURE 1 a deep cigarette mass moves along a compartment 43 in the direction of the arrows, under the influence of bands 6 and 44. 8 is a cigarette hopper of a packing machine (not shown) having a conveyor 57 which delivers cigarettes to the hopper, and a pivoted flexible guide 58 having cross-pieces which act as light weights and turn any skewed cigarettes, so that their axes are normal to the direction of movement of conveyor 57. Other feed conveyors similar to 57 and for feeding cigarettes to other hoppers (not shown) are marked 157 and 257 respectively.

In order to raise cigarettes emerging from the compartment 43 high enough to pass them to the conveyors 57, 157 or 257, there is provided a vertical conveying device 70. This is constituted by two band conveyors 71 and 72 whose neighbouring runs move upward, as shown by the arrows, and grip a thick column of cigarettes between them. The thickness of this column is determined by the relative speeds of bands 71-72 and the belt 6. In the example shown, the bands 71-72 travel at three times the speed of belt 6 so the thickness of the column is one-third of the depth of the mass in compartment 43. The speed ratio depends, of course, on the fact that the possible width between bands 70-71 is limited, as aforesaid. A few cigarettes are indicated at C but it will be understood that the mass of cigarette is continuous, and this is indicated by cross-hatching. It will be noticed that as the mass moves from compartment 43 to the conveyor device 70 it moves through a converging curved path, becoming re-arranged into a kind of swan-neck formation. This is brought about by the lower end of the conveyor 72 which hangs down freely but carries a large, heavy, cylindrical weight 73 in its bight. The weight is held against lateral movement by sprung guide rollers 82. A fixed guide 74 extends from the conveyor band 44 to the conveyor band 72 so as to confine the cigarettes to the desired path. The mass is kept in the desired order laterally by flanges 75 rotatable on a shaft 76 which passes through the hollow interior of the weight 73.

The bands 71-72 can be driven in any desired manner, according to the machinery in which this apparatus is incorporated, but a convenient method is by small electric motors coupled to shafts 76A and 76B, which carry driving pulleys 77-78 for the bands. Suitable tension pulleys may be provided for the band 71, but the tension of band 72 is provided by the weight 73.

Various materials are suitable for the belts 71-72 but a smooth surface is desirable. The plastic substance known as Mylar (R.T.M.) gives good results and any smooth-surfaced material with substantially the same coefficient of friction as Mylar (R.T.M.) is satisfactory.

The mass in compartment 43 moves into contact with the band 71 at the bottom and band 72 at the top and the advancing mass is accelerated by these two bands. At the broken line A—A, slippage occurs between the mass and the belts but this diminishes to zero at BB. The bands 71 and 72 are backed by smooth guides 79.

Owing to the friction between the cigarettes and the bands 71-72 and the internal friction between cigarettes, the cigarettes at BB are not subjected to undue compression by the weight of the cigarettes above them in the column.

A small rod 80, or similar device, around which is wrapped a piece of flexible material 81, is provided to span the gap between the two band rollers which support the bands 6 and 71. The material 81 can be extended, or contracted, by unwrapping, or wrapping, it a little. Nylon is a suitable material for the part 81. The free end of the strip determines the exact position at which cigarettes come into contact with band 71. The adjustment is useful to get the best results with different kinds of cigarettes. In transit up the conveying device 70 the friction between bands and cigarettes and the internal friction between the cigarettes is sufficient to convey the cigarettes without local displacement among the cigarettes.

The arrangement shown in FIGURE 2 is of the same general kind as that shown in FIGURE 1, and parts which are identical bear the same references and will not be particularly described. In this case the band which engages the upper surface of the cigarette mass 43 is arranged somewhat differently but this has nothing to do with the present invention and its operative face is positioned as in FIGURE 1 and it is therefore labelled 44.

It will be seen that the weight 73 has been dispensed with and the lower bight of the band 74 is supported on a pulley 83 having a shaft 84. The shaft is positioned so as to provide a converging curved path of substantially the same shape as in FIGURE 1. The position of shaft 84 has been determined by lengthy trials of the apparatus shown in FIGURE 1, but adjustment for its position may be provided. Side cheeks (not shown), confine the cigarettes laterally in the neighbourhood of the converging curved passage. At the convex side of this path, which is defined by the band 71, is a smooth concave support 85 which maintains the band at the desired curvature. Another curved member 86 engages the cigarettes as they pass from the outlet of the conveying device 70 on to the conveyors 57, 157 and 257. The member 86 is fixed at one end to a housing 87 so an excess of cigarettes will tend to distend it. It is connected to a micro switch 88 and if there is an excess of cigarettes due to the stoppage of a packing machine the switch will operate to cause the supply of cigarettes to the conveyor device 70 to diminish. In the particular case of the specification quoted earlier, this is done by shifting the back plate which forms the other end of the compartment 47.

It will be noted that the upward path of conveyance of the cigarettes slopes backwards with respect to the horizontal mass in the compartment 43. A suitable angle may be up to 10° and it is sometimes useful to be able to have the conveying device at an angle to the vertical to suit different layouts of the machinery concerned.

It was stated earlier that the pulleys 77 and 78 may

75

be driven by electric motors and these are indicated in FIGURE 2 at 89, to show suitable driving means. In practice, however, the driving means would be chains or the like driven by other moving parts of the machinery concerned.

The embodiments of the invention which have been described are intended particularly for use with cigarettes, but it will be appreciated by those skilled in the art that the apparatus would be equally suitable for use with 10 cylindrical cigars or filter rods used in the cigarette trade. These filter rods are much harder than cigarettes so they can be more tightly compressed between the bands 71 and 72 if necessary. The term cylindrical rodlike article is intended to include not only cigarettes and filter rods 15 but also filter cigarettes, where a large part of the length of the cigarette consists of a filter.

What I claim as my invention and desire to secure by Letters Patent is:

1. Apparatus for moving a mass of cylindrical rodlike articles from a low level to a higher level, the mass having a width equal to the length of an article, comprising a conveying device consisting of two conveyor bands having neighbouring runs which move upward, and are spaced apart by a dimension not substantially exceeding 25 3 inches, to define a passage extending from the low level to the higher level, means for driving the bands to cause the neighbouring runs to move upward, means for urging a mass of articles into contact with the bands at the lower end of the passage, comprising a bottom conveyor for 30 the mass, the depth of the mass at the low level exceeding the space between the neighbouring runs of the bands, and means for reducing the cross-section of the mass as it moves into contact with the bands at the lower end of the passage, the bottom conveyor being movable at 35 a rate such that the speed ratio between the conveyor and the said bands is equal to the reduction in cross-section of the mass in passing from the lower level into the passage.

2. Apparatus as claimed in claim 1 wherein the means 40 for reducing the cross-section of the mass comprises a guide means for the lower end of that band which engages the upper part of the mass at the low level, the guide means constraining the lower end of the band to follow a curved path which extends downwards lower than the top of the mass at the low level.

3. Apparatus as claimed in claim 1, in which the means 45 for reducing the cross-section of the mass consists in providing that one of the said bands, which engages the upper part of the mass at the low level, with a cylindrical 50 weight which hangs in the lower loop of the band to tension it, and cause the loop to define a concave curve forming the upper side of a path of converging curved shape, while the other of said bands is guided to define a convex curve forming the lower side of said path, the 55 path having an entry of a depth equal to the depth of the mass at the low level, and a thickness at the exit equal to the cross-section of the mass to be carried up between the neighbouring runs of the bands.

4. Apparatus as claimed in claim 1, in which the means 60 for reducing the cross-section of the mass consists in providing a pulley, rotatable on a fixed axis, around which that conveyor band which engages the upper part of the mass at the low level, turns, said pulley being positioned to cause the band to define a convex curve forming the 65 upper side of a path of converging curved shape, while the other of said bands is guided to define a convex curve forming the lower side of said path, the path having an entry of a depth equal to the depth of the mass at the low level and a thickness at the exit equal to the cross-section of the mass to be carried up between the neighbouring runs of the bands.

5. Apparatus as claimed in claim 4 wherein the axis 70 of the pulley is at substantially the same level as the top of the mass of articles at the low level.

6. Apparatus as claimed in claim 1 wherein the means for urging the mass of articles into contact with the bands at the lower end of the passage additionally comprises a top conveyor for the mass so that the depth of the mass at the low level is the space between the top and bottom conveyors.
